NEUTRALIZING CIRCUIT FOR SCREEN-GRID
TUBES

Werner Buschbeck, Berlin, Germany, assignor to
Telefunken Gesellschaft für Drahtlose Tele-
graphie m. b. H., Berlin, Germany, a corpora-
tion of Germany

Application April 3, 1935, Serial No. 14,494
In Germany April 3, 1934

4 Claims. (Cl. 179—171)

The present invention is concerned with ways and means adapted to neutralize or compensate residual capacitances existing in screen-grid tubes between the control electrode and the plate, and which are especially suited for short-wave systems.

Owing to the presence of the screen-grid the capacitance existing between plate and control electrode is effectively diminished. The residual capacitance which may remain is neutralizable with such means as are known from triode tubes as long as this assumption is fulfilled, that the screen-grid so far as alternating current voltage is concerned is at cathode potential. And this assumption may be supposed to be practically satisfied where not unduly high tube capacities are dealt with, where the waves are long, and where an adequately high blocking condenser is provided between the screen grid and the cathode. Where however shorter waves are concerned, and where screen-grid tubes are designed for large powers, the said assumption is no longer satisfied. Of necessity, the connecting leads between the electrodes and the lead-in points or seals across the vacuum vessel (with the exception of the plates in water-cooled tubes) are of a certain length and thus have an inductive reactance which, where short-waves are involved, is no longer negligibly small in comparison with the capacitive reactance residing in the corresponding intermediate-electrode capacitances. Even if the supposition were made that the capacity interposed between the screen-grid and the cathode were free from loss (leakage) and infinitely high, the screen grid can no longer be considered, as regards high-frequency, to be at cathode potential. However, this means that in the case of the arising of a plate alternating voltage, there is impressed upon the screen-grid an alternating voltage of the same frequency, but a phase displacement angle of 180 degrees, the amplitude of which is governed by the voltage division due to the capacitance (C_{sa}) prevailing between the screen-grid and the plate, and the lead inductance (L_s) existing between the screen-grid and the cathode. In other words, the screen-grid, so far as the control electrode is concerned, acts like a further anode or plate, which, to be sure, is subject to alternating voltages of lower amplitude, but which because of the considerable capacity between the screen-grid and the control electrode (C_{gs}) is in rather close coupling relation with the latter. In view of the fact that the alternating voltages at the plate and the screen-grid

present a relative phase angle of 180 degrees, it is possible by choosing suitable dimensions or values for the inductance existing between the screen-grid and the cathode (L_s) to secure perfect neutralization for a very definite wave-length. However, such neutralization is inadequate in practical working inasmuch as it would be lost and lacking as soon as there is a change in the wave-length, while the restoring of the state of neutralization would be attended with a good deal of tedious and time-consuming readjustment in every given instance. The present invention, therefore, discloses ways and means incorporated in a circuit organization whereby neutralization of the residual capacitance between control grid and plate will be insured under conditions unaffected by the wave-length or frequency.

According to the invention, by the simulation of all of the capacitances existing inside the tube, a point corresponding to the screen-grid itself is created, whence neutralization is effected. Under certain circumstances, it may here be permissible to disregard the capacities existing between plate and cathode, or between screen-grid and cathode, which anyway are always inherently small.

A number of exemplified embodiments of the basic idea of the invention are shown in the accompanying drawings, wherein Fig. 1A is a screen-grid circuit neutralizing arrangement according to the invention; Fig. 1B is a circuit equivalent to that shown in Fig. 1A, but redrawn in a different form; Fig. 2 is a similar form of circuit as shown in Fig. 1B utilizing tubes in push-pull according to the invention; Fig. 3A is a modification of the arrangement shown in Fig. 1A, but employing grid-circuit neutralization, and Fig. 3B is an equivalent and redrawn circuit.

Referring in particular to Fig. 1A, a stage of amplification is shown as comprising a screen-grid tube V whose cathode is denoted by K, the control grid by G, the screen-grid by S, and the plate or anode by A. The plate potential, by ways and means known in the art, is supplied by the aid of a radio frequency choke coil D, while the plate oscillation circuit LCC is relieved of direct voltage by the provision of a blocking capacity B. The radio frequency control voltage is impressed upon the grid circuit across the terminals 0 and 1. The screen-grid potential is furnished from a source of voltage E_{sg} . The inductances of the leads or wires brought to the various electrodes, in which are figured also the

leads disposed inside of the vacuum vessel, are indicated in the form of lumped inductances L_g , L_s and L_k . According to this invention, neutralization under conditions independent of frequency or wave-length is secured by the fact that all of the capacitances existing within the tube as well as the inductances of the leads brought to the different electrodes are simulated; in fact, such simulation, as it were, constitutes a homologous complement of the tube V including all of the leads and wires.

The neutralizing action of Fig. 1A may be more readily understood by reference to Fig. 1B. The object of the invention is to arrange the circuit in such a way that regardless of frequency, voltage between output terminals will not produce any voltage between input terminals. This result can be achieved by making the entire network symmetrical in the sense that each of the input terminals has a potential which is intermediate between the potentials of the output terminals in the same proportion. While not the only way to obtain this result, the simplest way is to duplicate all the impedances of the tube system (shown in the upper half of the network of Fig. 1B) by a similar set of impedances (shown in the lower half of Fig. 1B) and which may be called the neutralizing network. In this way it is obvious that the potentials of the input terminals are each half way between the potentials of the output terminals and since the input terminals have the same potential (in the absence of impressed signal voltages) in spite of voltage across the output, the object of the invention is attained.

The inductances serving to simulate the inductances associated with the tube are characterized by a supplemental index N (thus: L_{Ng} , and L_{Ns}), whereas the simulations in regard to capacitance are indicated and designated by N_{Ng} (grid-cathode capacitance), N_{Gp} (grid-plate capacitance), N_{Sg} (screen-grid/control-grid capacitance), and N_{Sp} (screen-grid/plate capacitance). Condenser N_{Kp} (cathode-plate capacitance) and N_{Sk} (screen-grid/cathode capacitance) may be omitted, under certain circumstances, provided that inherently low capacitances are involved, and that the waves are not unduly or abnormally short.

Fig. 1B represents merely the same circuit organization drawn in a different form, with the tube being imagined to be resolved into its constituent elements. The reference numerals are the same as in Fig. 1A, and the symbols used for the different electrodes of the tube are in the same form as shown in Fig. 1A.

For the balance and simulation of the capacitances and inductances arising inside the tube, the use of an inactive tube similar to the tube to be neutralized is particularly well suited. In this respect the several neutralizing capacitances and inductances shown in Figs. 1A and 1B may be considered as corresponding to the inter-electrode capacitances and lead inductances of the inactive tube. According to the prior art, such tube phantoms have merely been employed for the purpose of allowing of line (circuit) reduction in transmitter stages containing more than one tube by that a working tube was replaced by a phantom corresponding to it. However, according to this invention such a simulation is utilized for a different purpose and in a different sense, i. e., with the end in view to securing neutralization in an amplifier valve under conditions independent of the frequency.

Inasmuch as the simulation of a capacity, under certain circumstances, is more readily feasible than that of an inductance, it may if conditions are appropriate, be feasible to interpose in the leads of the alternating potential applied to the different electrodes, condensers, and to render the resultant impedance (apparent resistance) either ohmic or capacitive.

Fig. 2 shows an extension of the arrangement shown in Fig. 1B for a single tube, as applied to a push-pull arrangement. The reference symbols referring to the second tube are characterized by primes (''). It will be unnecessary to give further explanations for this circuit diagram.

It is known that the voltages required for such compensation or balancing may be derived either from the grid or from the plate circuit of the stage in question. Whereas in the case of Figs. 1A and 1B neutralization was effected from the plate end, Figs. 3A and 3B illustrate a circuit organization in which neutralization, in a way as known basically from the prior art, is effected from the grid. The input circuit of the stage contains the inductance L_1 as well as the condensers C_1 ; the output circuit contains the inductance L and shunt condenser C ; the other circuit elements are the same as those used in the preceding figures. Fig. 3B shows a modified representation of the circuit scheme illustrated in Fig. 3A in order that the homologous or mirror-picture simulation may be made more clearly understandable.

What I claim is:

1. A circuit arrangement comprising a tube having a cathode, a control grid, a screen grid electrode within said tube intended to operate at unvarying potential but actually fluctuating in potential when operated at very high frequencies due to unavoidable or slight impedances to high frequencies in the circuit between said screen grid electrode and cathode, input and output circuits associated with said tube, and means for counteracting energy transfer from output to input circuits resulting from said fluctuating potential, said means comprising a pair of series-connected inductances having their common terminals connected to the tube cathode, an inductance connected to the control grid, the opposite end of said last mentioned inductance being connected to the unconnected terminal of one of the pair of inductances by means of a condenser, said opposite end of said inductance being also connected to the unconnected terminal of the other inductance of the pair by means of a pair of series-connected condensers.

2. A neutralizing circuit for an electron discharge device provided with anode, cathode, control grid and screen grid electrodes, comprising a first inductance of a value substantially equal to the self-inductance of the cathode lead having one end connected to the cathode, a first capacity of a value substantially equal to the grid-cathode capacity having one end connected to the other end of said first inductance, a second inductance of a value substantially equal to the self-inductance of the screen grid lead having one end connected to the cathode, a second capacity of a value substantially equal to the screen grid-anode capacity having one end connected to the other end of said second inductance, a third inductance of a value substantially equal to the self-inductance of the control grid lead having one end connected to the control grid and

the other end connected to the other end of the first mentioned capacity, and a third capacity of a value substantially equal to the control grid-anode capacity connected between the last mentioned connection and the other end of said second capacity.

3. The circuit according to the invention defined in the preceding claim wherein a capacity of a value substantially equal to the screen grid-control grid capacity is connected between the non-common terminals of the second and third capacities.

4. A neutralizing circuit of bridge form for an electron discharge device provided with anode, cathode, control grid and screen grid electrodes, comprising a condenser in the output circuit of said device connected between said anode and cathode, a first inductance of a value substantially equal to the self-inductance of the control grid lead, a second inductance of a value substantially equal to the self-inductance of the screen grid lead, a direct connection from one terminal of said first inductance to said control grid lead, a direct connection from one terminal of said

second inductance to said cathode, the other terminals of said two inductances being connected together through a condenser whose value is equal to the value of the internal capacity between said control grid and screen grid electrodes, 5 two serially connected condensers arranged in parallel with respect to said last-named condenser, one of said two serially arranged condensers having a value substantially equal to the value of the internal capacity between said anode 10 and control grid, the other of said two condensers having a value substantially equal to the internal capacity between said anode and screen grid, a connection between the junction point of said two condensers and said output circuit, and an 15 inductance and a condenser connected in series between the cathode and said other terminal of the first inductance, said inductance being of a value substantially equal to the self-inductance of the cathode lead and said condenser being of 20 a value substantially equal to the value of the internal capacity between said control grid and cathode electrodes.

WERNER BUSCHBECK.
